UNITED STATES PATENT OFFICE.

NOAH COOL, OF NEAR ARCANUM, OHIO.

BRIDGE-ANCHOR.

1,162,038.

Specification of Letters Patent. Patented Nov. 30, 1915.

Application filed June 23, 1913. Serial No. 775,174.

To all whom it may concern:

Be it known that I, NOAH COOL, citizen of the United States, residing near Arcanum, in the county of Darke and State of Ohio, have invented certain new and useful Improvements in Bridge-Anchors, of which the following is a specification.

My invention relates to bridge construction and particularly to anchoring means for securing bridges to their abutments.

Much difficulty is experienced and considerable damage results from periodic freshets or floods, which lift bridges such as are usually found over brooks, creeks and rivers, from their foundations.

The object of the invention is to simplify the structure as well as the means and mode of operation of bridge anchors, whereby they will not only be cheapened in construction, but will be more efficient in use, economical in manufacture, readily applied by unskilled mechanics and unlikely to get out of repair.

A further object of the invention is to provide such bridge anchoring means, which while securely holding the bridge to its adjusted position on the abutments, will provide for a certain amount of elasticity in the connection, whereby the bridge will be permitted a limited independent movement to compensate for contraction and expansion.

It has been found in practice undesirable to secure a bridge rigidly to its abutments. The present invention, while designed to secure the bridge against displacement, will permit sufficient free movement thereof to compensate for vibration of the structure.

While the invention is herein shown and described in connection with bridge structures, it is to be understood that it is equally applicable to building structures for securing the frame work to the foundation.

With the above primary and other incidental objects in view as will more fully appear in the specification, the invention consists of the features of construction, the parts and combination thereof, and the mode of operation or their equivalents as hereinafter described and set forth in the claims.

Referring to the drawings, Figure 1 is a perspective view of one end of a bridge of ordinary construction, to which the invention has been applied. Fig. 2 is a detail perspective view of the same construction, showing a modification of the anchor bolt heads. Fig. 3 is a perspective view of one end of a bridge of similar construction, showing a

modification of the anchor devices. Figs. 4, 5 and 6 are detail perspective views illustrating modifications of the connections between the anchors and the bridge structure.

Like parts are indicated by similar characters of reference throughout the several views.

While in the drawings the invention has been shown as applied to a timber or wooden bridge of ordinary construction it is to be understood that it may likewise be applied to metal bridges constructed of channel or I beams or plates in the ordinary manner.

Referring to the drawings, 1 is the abutment or foundation upon which the bridge rests. Upon this foundation are supported the girders or stringers 2—2. Inclined upward from the stringers or girders 2—2 are the trusses 3. The stringers or girders may be arranged singly as shown in Fig. 3 or each girder may be double, as shown in Figs. 1 and 4. To the girders 2 are secured in transverse relation the floor planks 4. This is the usual construction of small bridges.

It is the usual practice in placing small bridges to rely upon the weight of the bridge to retain it in proper position upon its foundation or abutment. The weight of the bridge however is frequently found insufficient under flood conditions and the structure is frequently shifted from its position or washed entirely from the foundation. To enable the bridge to resist the pressure of flood waters, there is provided in the construction shown in Fig. 1 a transverse rod or bar 5, projecting through longitudinal slots 6 in the girders or stringers 2. Embedded in the masonry or concrete abutments or piers 1 are perpendicular anchor bolts 7, having eyes 8 at their upper extremities through which the transverse bar or rod 5 projects. The anchor bolt 7 is preferably located upon opposite sides of the girders or stringers 2 as shown in Fig. 1, but in the event that a less number of anchor bolts are to be employed, such bolts should be located on the down stream side of such girders.

To provide a convenient means of securing the anchor bolt in position, in the abutment or pier 1, the lower ends of such bolts are preferably provided with an eye 9, similar to the eye 8 at their upper ends. Through the eye 9 at the lower end of the bolt, there is preferably thrust a rod or bar 10. A transverse bar 10 of short length may be provided with each of the anchor bolts 7,

or a bar 10 of greater length may engage two of the anchor bolts, as shown in Fig. 1. It is to be understood that these bolts 7 and transverse bars 10, are to be located in the 5 abutment or pier, during the process of its erection. In lieu of the transverse bars 10, there may be provided upon each of the anchor bolts 7, a disk like head 11, as shown in Fig. 2, or the shank of the bolt may be 10 formed serpentine, as indicated at 12 in Fig. 2.

Links 13 are provided with an eye at one 15 end engaging the transverse rod or bar 5, and at their opposite end are engaged with the trusses 3 either by an eye formed in the link, engaging a stud 14, projecting from the truss 3, as in Figs. 2 and 3 or by bolting them directly to the trusses as in Fig. 1, or 20 in other suitable manner. These links 13 positively connect the super structure with the pier or abutment. The transverse rod or bar 5, extending through the slot 6 and over the lower portion of the girders, prevents the bridge from being elevated or floated 25 upward off of its foundation, while the eyed ends 8 of the bolts 7, projecting above the foundation adjacent to the girder on the down stream side, prevent the bridge from being shifted laterally upon its foundation.

30 This anchorage construction is simple in its form and may be readily constructed by any blacksmith and may be applied to a bridge by persons otherwise unskilled in bridge construction.

35 In Fig. 3 there is shown a modification of the construction before described in which a transverse plank 15, forming a portion of the bridge floor is substituted for the transverse bar or rod 5. The transverse plank 40 15 is not positively secured in any way to the girders or stringers 2, but merely rests upon the top of the girder or stringer and is secured to the foundation 1 by the bolts 16 embedded therein. These stud bolts 16 45 may be provided with the eyes 9 and the transverse bar 10 at the lower extremity, or they may be provided with the disk heads 11 or the serpentine form 12 as before mentioned.

50 The girders 2 in both constructions are free to expand and contract independent of the transverse bar 5 or the transverse plank 15. While these constructions secure the bridge to the foundation, they do not hold 55 the bridge rigidly thereto, but permit sufficient movement to compensate for the vibration of the structure.

56 In Fig. 4 there is shown a double girder construction, with which is employed an M shaped yoke 17. The anchor bolts or studs 16 in this case pass through suitable openings in the yoke intermediate the girders 2 and are provided with nuts 18. It is to be noted that the yoke 17 is not secured to the 65 girders, but rests on the abutment 1, leaving

the girders free to move longitudinally beneath the yoke.

In Fig. 5 there is shown a single girder construction employing a transverse bar 20 resting upon the top edge of the girder 2 70 and connected with the eye 8 of the anchor bolt 7 by the link 21. The truss member 3 is connected with the same eye 8 of the anchor bolt 7 by a link 22. The bar 20 is not connected or attached to the girder 2 but 75 merely rests thereon. The links 21 and 22 are pivotally connected with the anchor bolt 7, thereby permitting a limited movement or vibration of the bridge structure. In this construction the bar 20 is employed in lieu 80 of the transverse bar 5 of Fig. 1 and the plank 15 of Fig. 3.

In Fig. 6 is shown a further modification, somewhat similar to that disclosed in Fig. 4, but applicable to a single girder construction. In this construction an inverted U shaped yoke 23 is employed, the lower out turned ends 24 of which rest upon the abutment 1 to which they are secured by the anchor bolts 16. The girder 2 extends 90 through the inverted U shaped yoke but is not attached thereto. The yoke 23 being supported upon the abutment, leaves the girder 3 to shift longitudinally thereunder.

95 From the above description it will be apparent that there is thus provided a device of the character described, possessing the particular features of advantage before enumerated as desirable, but which obviously is susceptible of modification in its 100 form, proportion, detail construction or arrangement of parts, without departing from the principle involved or sacrificing any of its advantages.

105 While in order to comply with the statute, the invention has been described in language more or less specific as to certain structural features it is to be understood that the invention is not limited to any specific details, but that the means and construction herein described comprise but one mode of putting the invention into effect, and the invention is therefore claimed broadly and in any of its possible forms or modifications within the scope of the appended claims.

110 Having thus described my invention, I claim:

1. In a structure as described, a foundation, girders resting loosely upon the foundation and capable of longitudinal movement in relation therewith and having elongated openings therein, anchor studs embedded in the foundation and projecting thereabove in positions beside the girders and limiting the lateral movement thereof, and a retaining member extending transversely through the elongated openings of the girders and connected with the anchor bolts, limiting the vertical movement of the girders. 115 120 125 130

2. In a structure capable of limited shifting movement as described, a plurality of girders arranged in parallel relation, a foundation upon which the girders loosely rest in relation with which the girders are longitudinally movable, anchor bolts projecting from the foundation, and a retaining member common to all the girders fixed in relation with the foundation but independent of which the girders are movable, arranged in transverse relation therewith and connected to the anchor bolts, substantially as and for the purpose specified.
3. In a bridge construction, a foundation, girders capable of longitudinal movement resting on the foundation and having transverse openings therein, anchor bolts embedded in the foundation at the side of the girders and beyond which the girders project, eyes formed in the upper ends of the anchor bolts alined with the openings in the girders, and a retaining bar arranged in transverse relation with the girders projecting through the transverse openings thereof and laterally therebeyond, such lateral extensions of the transverse member each being engaged with the eye of the adjacent anchor bolt.
4. In a non-rigidly attached structure as described, a foundation, girders resting
- loosely upon the foundation and capable of longitudinal movement in relation therewith, and retaining means arranged in transverse relation with the girders independent of which the girders are longitudinally movable and connected with the foundation adapted to prevent the vertical and lateral displacement of the girders but permitting the longitudinal movement thereof independent of the retaining means, substantially as and for the purpose described.
5. In a bridge construction, a foundation, girders resting on the foundation, vertically disposed anchor bolts located in the foundation adjacent to the girders, eyes formed in the opposite ends of the vertical anchor bolts, a transverse bar engaged in the terminal eyes at each end of the anchor bolts, the transverse bars at the lower ends of the bolts being embedded in the foundation, the transverse bars at the opposite ends of the anchor bolts engaging the girders, said girders being capable of longitudinal adjustment independent of the anchor bolts.

In testimony whereof, I have hereunto set my hand this 9th day of June, 1913.

NOAH COOL.
